Attorney

UNITED STATES PATENT OFFICE.

JOSEPH BERMAN, OF BALTIMORE, MARYLAND.

BRIDLE FOR BROOMS AND SIMILAR DEVICES.

Application filed July 6, 1922. Serial No. 573,064.

To all whom it may concern:

Be it known that I, JOSEPH BERMAN, a citizen of the United States, residing in the city of Baltimore and the State of Maryland, have invented a certain new and useful Bridle for Brooms and Similar Devices, of which the following is a specification.

My invention relates to a bridle for brooms, brushes and similar devices, and an object of the invention is to provide a device of this nature which will increase the longevity of the broom or brush to which it is applied.

Another object of the invention is to provide a bridle which is adjustable and adapted to be varied in size to fit brooms of different sizes.

A further object of the invention is to provide an improved means for clamping the bridle against the broom head.

A still further object of this invention is to provide a bridle which is of simple construction, which is durable and which may be manufactured at comparatively low cost.

Other objects of the invention will be apparent from the following description and the accompanying drawings in which:

Fig. 1 is a side elevation of the ordinary house broom showing one form of my bridle applied thereto.

Fig. 2 is a perspective view of a slightly different form of bridle.

Fig. 3 is a fragmentary perspective view showing a modified form of clamping arrangement.

Fig. 4 is a perspective view of the screw clamp provided with a locking key.

Referring more particularly to the drawings, A designates the head or bristles of the broom having connected thereto, as shown, the usual handle B.

The bridle comprises the upper and lower bands 1 and 2, respectively, adapted to encircle the broom head, and connected together by the front side strips 3 and 4 and the back side strips 5 and 6, the latter side strips being shown in dotted lines in Fig.

1. The form of bridle shown by Fig. 2 is almost identical with the form shown by Fig. 1 excepting that the front side strips 3 and 4 are dispensed with in order that the bands 1 and 2 may be more easily varied in circumference to adapt them to fit brooms of various sizes. The connecting strips in the

form shown by Fig. 2 are represented by 55 the reference characters 5' and 6'. The other parts of the bridle are the same as those of the bridle shown by Fig. 1 and for the sake of clearness in the description of my invention, reference should be had to Fig. 60 2 for illustration, unless other figures of the drawing are specifically referred to.

The bands 1 and 2 are divided at their front central points and have overlapping portions in sliding contact with each other, 65 each of said bands having guides formed by flanges 7, 8, 9, and 10 bent as shown more particularly by Figs. 2 and 3, the said guides being arranged near each of the edges of each of the bands and being adapted to receive the opposite end of the respective band, as will be readily apparent from an inspection of the drawings without further description. It will thus be seen that the bands may be varied in circumference so that 75 the bridle will fit brooms, brushes, and similar devices of different sizes.

The upper band 1 has secured thereto, at the points shown, the positioning flanges 11 and 12 which are adapted to fit under the 80 threads of the stitching 13 of the broom head and thus assist in holding the bridle in place on the broom head.

The lower band 2 has in the rear side thereof the lugs 14 and 15 which have screw 85 threaded apertures therein adapted to receive the screw clamps 16 and 17 which pass through holes 18 and 19 in the front side of the lower band 2, the said holes being in alignment with the screw threaded apertures 90 in the lugs 14 and 15. The screw clamps 16 and 17 each have a key 20, as shown more clearly by Fig. 4, fixed thereto near the heads thereof, which key is designed to fit in the key-way 21 formed in the lower band 95 2 and which lead from each of the holes 18 and 19. It will be appreciated that I have provided a simple means for clamping the broom bridle against the broom head.

When the bridle is placed on the broom head, 100 the screws are passed through the holes 18 and 19, pressure is applied to the sides of the band 2 so that said band is clear of the path of the key 20 when the clamp screws 16 and 17 are rotated and threaded into the screw 105 threaded lugs 14 and 15 until the broom bridle tightly clasps the sides of the broom head when the keys 20 are permitted to slide

into the key-ways 21 and thereby prevent the screw clamps from unscrewing and becoming loose.

To permit of the bridle shown by Fig. 2 being used with a smaller broom, there is provided in the lower band 2 additional holes 22 and 23 stamped through the overlapping portions of the band, one of said holes being arranged to align with the hole

18 and the other with the hole 19 when the band is contracted to fit the smaller broom, the screws then being passed through the holes 18 and 22 and 19 and 23, respectively, and threaded into the lugs 14 and 15 as before described.

As an alternative arrangement, and in order to provide a finer adjustment of the circumferences of the bands 1 and 2, I may substitute for the holes 18 and 19 in the lower band 2 of the bridle, the slots 24 and 25 having a plurality of key-ways 26 to accommodate the key 20 of the screw clamps 16 and 17. This construction is shown by Fig. 3. Each of the slots is always opposite one of the lugs 14 and 15 when the bands are contracted so that the clamping screws may be readily inserted in said lugs as hereinbefore described to clamp the bridle in place on the broom head.

From the above description, it will be understood that I have provided a bridle for brooms, brushes and similar devices adapted for brooms of various sizes and designed to prevent the broom bristles or straws from wearing more on one side than on the other, that will provide a brace for the broom or other device to prevent its undue and excess bending during its use and that will, in short, greatly prolong the life of the broom to which my invention is applied.

It is obvious that certain minor changes may be made without departing from the spirit or the scope of my invention as defined by the appended claims.

Having thus described my invention, what I claim and desire to secure by Letters Patent of the United States is:

1. A broom bridle comprising upper and lower bands, the upper band being adapted to encircle the broom head at the stitching thereof and the lower band being adapted to encircle the broom head below the stitching thereof, side strips connecting said bands, means on said upper band adapted to cooperate with the broom head stitching to hold the bridle in place on the broom head, and means associated with said lower band for clamping said lower band against the broom head.

2. A broom bridle comprising upper and lower bands, the upper band being adapted to encircle the broom head at the stitching thereof and the lower band being adapted to encircle the broom head below the stitching thereof, side strips connecting said bands,

said bands terminating in overlapping portions in sliding contact with each other to enable the circumferences of said bands to be varied for use with brooms of different sizes, means on said upper band cooperating with the broom stitching to hold the bridle in place on the broom head, and means associated with said lower band to clamp said lower band against the broom head.

3. A broom bridle comprising upper and lower bands, the upper band being adapted to encircle the broom head at the stitching thereof and the lower band being adapted to encircle the broom head below the stitching thereof, side strips connecting said bands, said bands terminating in overlapping portions in sliding contact with each other to enable the circumferences of the bands to be varied for use with brooms of different sizes, said overlapping portions having flanges bent to form guides for the opposite overlapping portions of the bands, means on said upper band adapted to cooperate with the broom head stitching to hold the bridle in place on the broom head, and means associated with said lower head for clamping said lower band against the broom head.

4. A broom bridle as defined by claim 2, said last mentioned means comprising screws passing through the lower band and between the straws or bristles of the broom.

5. A bridle for brooms comprising upper and lower bands and side strips connecting said bands, said bands having overlapping portions in sliding contact with each other to permit of the bands being varied in circumference to accommodate brooms of different sizes, said lower band having screw threaded apertures in one side thereof and other apertures in the opposite side of the band and in alignment with the screw threaded apertures, and screws passing through said apertures for clamping the bridle against the broom head.

6. A bridle for brooms and similar devices comprising upper and lower bands adapted to encircle the broom head, side strips connecting said bands, said bands having overlapping portions in sliding contact with each other to enable the bands to be varied in circumference to accommodate brooms of different sizes, screw threaded apertures in one side of said lower band, elongated slots in the opposite side of said lower band, each of said slots being aligned with one of said screw threaded apertures, and screws passing through said slots and apertures for clamping said lower band against the broom head.

7. A bridle for brooms and similar devices comprising upper and lower extensible and contractible bands, side strips connecting said bands, screw threaded apertures in one side of said lower band, slots in the opposite side of said lower band, screws passing through said slots and apertures for clamp-

ing the bridle in position on the broom head, and means for locking said screws in a certain position longitudinally of the slots.

8. A bridle for brooms and similar devices comprising upper and lower extensible and contractible bands adapted to encircle the broom head, side strips connecting said bands, screw threaded apertures in one side of said lower band, other apertures in the

opposite side of the lower band aligned with 10 said screw threaded apertures, screws passing through said apertures, key-ways in said lower bands, keys on said screws cooperating with said key-ways to hold said screws in locked position.

15

In testimony whereof I affix my signature.

JOSEPH BERMAN.
